PROPELLER SHANK FORMING PRESS

Frederick A. Gruetjen, Milwaukee, Wis., assignor
to A. O. Smith Corporation, Milwaukee, Wis.,
a corporation of New York

Application March 3, 1945, Serial No. 580,894

9 Claims. (Cl. 78—96)

1

This invention relates to a propeller shank forming press.

The object of the invention is to provide a press for flattening the blade end of a shank section of a hollow steel propeller to match the thrust and camber faces of the body section of the blade.

Another object of the invention is to provide an apparatus which will fit between the platens of a standard press and which will form the larger 10 conical end of a shank to flatten the same.

Another object is to provide for simple mandrel mechanism for supporting the blank intermediate the dies as one of the dies approaches the other, to maintain the blank centered so that each die 15 operates thereon simultaneously and in a given amount.

Another object is to provide a collapsible mandrel against which the end of the blank is formed and which can be readily inserted and withdrawn 20 from the blank.

Another object is to provide for rapid loading and unloading of a press of the class referred to.

Other objects and advantages will be set forth in the description of an embodiment of the invention illustrated in the accompanying drawings.

In the drawings:

Figure 1 is a schematic side elevation of the press with the dies closed upon a blank;

Fig. 2 is an enlarged central transverse vertical section through the dies and mandrel;

Fig. 3 is a similar vertical longitudinal section taken on line 3—3 of Fig. 2;

Fig. 4 is a horizontal section taken on line 4—4 of Fig. 1 without the blank;

Fig. 5 is a detail view in horizontal section showing the loading of a blank;

Fig. 6 is a detail vertical section taken on line 6—6 of Fig. 5 and showing the blank turned to a position for receiving the mandrel; and

Fig. 7 is a view similar to Fig. 1 showing the dies open.

The press comprises in general the ordinary base or platen 1 with an upstanding frame supporting the upper vertically movable cross head or platen 2 operated by a hydraulic cylinder or other suitable operating mechanism.

The invention comprises a unit which fits between the platens 1 and 2 of the press and which has a base 3 secured to the platen 1 and a movable top 4 secured to the upper platen 2. The base 3 carries a lower die 5 while the top 4 carries an upper die 6. The dies 5 and 6 have complementary faces for forming the larger end of a conical tubular blank 7 to match the shape of a blade section of a propeller.

2

The blank 7 is held by its circular hub end which is inserted in a clamp 8 and secured therein by a thumb screw 9. The clamp 8 is supported on a sleeve 10 vertically movable on a cylindrical upright post 11 secured in the base 3. The sleeve 10 is raised and lowered by a pair of levers 12, each pivoted at one end to an upstanding bracket 13 on base 3 and connected at the other end to the top 4 by links 14. The levers 12 have sliding blocks 15 which are pivoted to trunnions 16 on the sleeve 10. The blocks 15 are disposed approximately midway between the pivot points of the respective levers 12 so that as the top 4 is lowered and the dies come toward each other, the blocks 15 and sleeve 10 with its clamp 8 and blank 7 move downwardly at about half the speed of top 4, thereby bringing both dies into contact with the blank simultaneously and effecting forming of the blank substantially equally by both dies.

The clamp 8 is pivoted on sleeve 10 and a handle 17 serves to provide for manual rotation of the clamp between loading position for clamp 8 and operating position for the press.

A collapsible mandrel 18 is provided to be inserted in the blank 7 and serve to form the same internally as the dies 5 and 6 come together. The mandrel 18 is supported on a cross head 19 secured between sleeves 20 and 21 on a pair of spaced upright posts 22 and 23, respectively. The vertical movement of the sleeves and cross head is provided by a pair of levers 24 pivoted at one end to brackets 25 on base 3 and connected at the other end to the top 4 by links 26. Sliding blocks 27 in the levers 24 are pivoted on trunnions 28 on the respective sleeves. The vertical movement of mandrel 18 is obtained from the movement of top 4 in the same manner as the movement of clamp 8 is obtained therefrom.

For the purpose of moving mandrel 18 endwise 40 into and out of the blank 7, the mandrel is mounted on a slide 29 which operates in a guide 30 in the cross head 19. Operation of slide 29 is produced by air cylinder 31 pivotally mounted on the sleeves 21 and 22 beneath the cross head and having its piston rod 32 pivotally connected to a lever 33 which is in turn linked at its upper end to the slide 29 to move it in and out. The lever 33 is pivoted at its lower end to a fixed bracket 34 on the cylinder support.

The collapsible mandrel 18 comprises a pair of forming dies 35 and 36 and an intermediate wedge 37 which is longitudinally tapered in thickness and which is dovetailed to the dies 35 and 36. The dies 35 and 36 are removable from the wedge 37 and are prevented from forward movement, during tightening, by a bar 38 ex-

tending from clamp 8 and which is bifurcated at its end to engage the dies and leave the wedge free to move.

The mandrel 18 has a greater composite thickness at its end which is inserted in the blank 7 than at its support end. This requires that the dies 35 and 36 be disassembled from wedge 37 in order to remove each piece separately from the blank after forming. The pieces of the mandrel are then assembled again for a succeeding forming operation.

The mandrel is mounted in a manner compensating for tolerance variations in thickness of the blank so that the pressure of the dies 5 and 6 on the top and bottom of the blank will always be equalized through the mandrel. For this purpose, the wedge member 37 is adjustably mounted in a block 39 which has a vertical shaft 40 pivoted in bearings 41 spaced above and below the block. The bearings 41 are disposed in the arms of the slide 29. Coil springs 42 surround the shaft 40 between block 39 and bearings 41 and serve to keep the block centered and at the same time to allow it and mandrel 18 to be moved up or down to effect the compensation referred to.

Adjustment of the wedge 37 longitudinally of block 39 determines the thickness of the mandrel in position for the die forming operation.

For the purpose of holding the mandrel 18 against lateral pivoting on the trunnions 40, a latch 43 is fixed to a shaft 44 pivotally mounted in the arm supporting the upper bearing 41, the plates of the latch normally hanging on either side of the block 39 and preventing its lateral movement. When it is desired to manually apply the dies 35 and 36 to wedge 37, latch 43 is pivoted upwardly and wedge 37 pivoted laterally to expose its end for ready application of the dies. The wedge is then pivoted back to alignment with bar 38 and clamp 8, and the latch 43 dropped in place to hold it there.

The reciprocation of mandrel 18 and slide 29 in guide 30 is limited in retraction by the adjustable stop 45 at the rear of guide 30, and in its forward movement by the adjustable stop 46 at the end of bar 38.

The operation of the press in one complete cycle is as follows: the dies 5 and 6 are separated with top 4 in its uppermost position. The mandrel is retracted to a position where slide 29 engages stop 45. The latch 43 is manually pivoted upwardly and wedge 37 swung forwardly to receive dies 35 and 36 which are then applied thereto. The assembled mandrel 18 is then swung back to operating position and latch 43 is dropped.

To load the press, handle 17 is utilized to pivot sleeve 10 and bring clamp 8 forward. A blank 7 is then applied over bar 38 and inserted in clamp 8 and tightened by thumb screw 9. The sleeve 10 is then pivoted back to operative position where the blank 7 is disposed in alignment with the dies 5 and 6 and about midway therebetween.

The air cylinder 31 is then operated to cause mandrel 18 to enter the end of the blank until dies 35 and 36 engage the end of bar 38. Further movement of wedge 37 expands the mandrel to operative size. Then the press is operated by lowering platen 2 and top 4. This brings die 6 downward, and as it lowers toward die 5, the blank 7, clamp 8 and mandrel 18 are also lowered to maintain their position midway of the dies. As dies 5 and 6 engage the blank 7, the latter is formed upon the mandrel 18.

After forming, pressure on the dies 5 and 6

is released and air cylinder 31 operated to retract wedge 37 from the dies 35 and 36. The top 4 is then raised, separating dies 5 and 6 and raising the blank 7 from die 5. The handle 17 is again used to pivot the blank forwardly, thumb screw 9 loosened and the formed blank removed. The dies 35 and 36 are removed from the formed blank ready for assembly with wedge 37, as before described for a similar succeeding forming cycle.

In order to prevent jamming of dies 35 and 36 upon wedge 37 when the latter is retracted, it is preferable to provide a pair of spring latches 47 secured to the end of the respective dies 5 and 6 to engage the outer end of the dies 35 and 36 when the dies 5 and 6 are in closed position. The latches 47 prevent dies 35 and 36 from moving with wedge 37 and serve to break the latter loose without jamming.

20 The invention may have various embodiments within the scope of the accompanying claims.

I claim:

1. In apparatus for forming hollow metal articles, a pair of relatively movable dies having 25 complementary die faces, a mandrel made up of a plurality of interlocked parts assembled and disassembled by relative longitudinal movement, means to open and close the dies to form an article upon said mandrel, means to remove one part of said mandrel longitudinally from the article to thereby release the mandrel from the article, and means to pivot the mandrel from between the dies to an assembly position to assemble the parts thereof.

30 2. In apparatus for forming hollow metal articles, a pair of relatively movable dies having complementary die faces, a work holder for supporting an article between said dies, and means to move said dies relatively to each other, means connected to said first named means and synchronized in movement therewith, to move said work holder and article during closing of the dies at a rate maintaining the article equally spaced from said dies until both dies close upon 45 the article.

3. In apparatus for forming hollow metal articles, a pair of relatively movable dies having complementary die faces, a post fixed relative to one die and extending in the direction of 50 relative die motion toward the other die, a work holder slidably upon said post, a lever having one end operatively connected to the base of the apparatus and the other end operatively connected to one of the dies to move with said dies, and pivoted means connecting the center of said lever with said work holder to slide the holder vertically along the post upon which the holder is assembled as the dies are moved relative to each other to support the work substantially midway between the dies at all times.

4. In apparatus for forming hollow metal articles, an upper die, a lower die, means to move one of said dies relatively toward and away from the other, a work holder for supporting 65 an article horizontally between said dies, a lever disposed horizontally with respect to said work holder, means located midway between the pivot points of said lever between the lever and holder to pivotally support said work holder, and connections between said lever and said upper and lower dies to effect raising and lowering of said work holder with the raising and lowering of said movable die, and the pivotal connection between the holder and lever raising and lowering the work holder with the rais-

ing and lowering of the movable die at a ratio of approximately 1:2.

5. In apparatus for forming hollow metal articles, a fixed die member, a movable die member, means to move said movable die member toward and away from said fixed die member, a work holder disposed to support an article midway between said die members, and means connected to said movable die member and to said work holder to move said work holder at a speed of approximately one-half that of said movable die to maintain the article centrally between said dies and effect contact of the dies upon the article substantially simultaneously.

6. In apparatus for forming hollow metal articles, a fixed die member, a movable die member, means to move said movable die member toward and away from said fixed die member, a work holder disposed to support an article midway between said die members, and a lever connected to said means and to said work holder and operated by said means to move said work holder at a speed of approximately one-half that of said movable die to maintain the article centrally between said dies and effect contact of the dies upon the article substantially simultaneously.

7. In apparatus for forming hollow metal articles, a mandrel having a longitudinally tapered central wedge member and two forming die members interlocked therewith, means to drive the wedge member forwardly between the die members to provide for expansion and contraction of the mandrel by the relative longitudinal movement of the wedge and the die members, said mandrel being adapted to be disposed as a unit through one end of the tubular article to be formed, a separate bar extending into the article through the end opposite the end through which the mandrel is inserted and having a bifurcated end abutted against the die members of the mandrel to hold the same against movement as the wedge is driven forwardly to expand the mandrel, means to form the article upon the mandrel, and means to withdraw the central wedge from the mandrel to collapse the same and release the die members from the article.

8. In apparatus for forming hollow metal blanks, a mandrel disposed to enter a tubular blank being formed, a pair of relatively movable dies for forming the blank upon the mandrel, mechanical means to automatically reciprocate the mandrel in a direction at right angles to the

direction of closing of said dies to enter the same in the blank, and mechanical means to automatically reciprocate the mandrel in the direction of die movement to support the blank centrally of the dies during such movement.

5 9. In apparatus for forming hollow metal blanks, a mandrel disposed to enter a tubular blank being formed and comprising two forming members interlocked to a central wedge member movable longitudinally thereof, a pair of relatively movable dies for forming the blank upon the mandrel, means to reciprocate the mandrel in a direction at right angles to the direction of closing of said dies to enter the same in the blank, mechanical means to automatically reciprocate the mandrel in the direction of die movement to support the blank centrally of the dies during such movement, and cushion means disposed on each side of the outer end of the wedge of the mandrel for additionally locating the mandrel accurately between the dies when the latter are closed upon the blank to equalize the pressure of the dies through the mandrel.
